STERILIZING AND DISINFECTING APPARATUS

Henry Charles Gould, Grantham, England

Application May 10, 1945, Serial No. 593,030
In Great Britain January 12, 1944

9 Claims. (Cl. 34—87)

1

This invention relates to sterilizing and disinfecting apparatus and it refers more particularly to apparatus employed for sterilizing or disinfecting surgical dressings and analogous articles which are treated in drums introduced into a chamber supplied with high pressure dry saturated steam, and the invention has for its principal object to ensure the rapid and complete expulsion of all air from the drums and especially any air in the interstices of the goods themselves. Another object of the invention is to eliminate the personal equation in so far as the control of the flow of sterilizing medium or exposure of articles to atmosphere are concerned and thus to render the apparatus fool proof, and a further object is to expedite the sterilizing or disinfecting operation and to improve the subsequent drying of the goods.

According to the invention the sterilizing or drying medium, as the case may be, is directed upwardly through a sterilizing drum and the admission of the medium to and its escape from the drum are controlled by means which are conditioned by the positioning of the drum in situ within the sterilizing chamber.

To this end the sterilizing chamber is provided with a steam or air admission connection so constructed as, when a dressings drum is seated thereon, to combine therewith to form an automatic coupling, and the dressings drum is provided, in its base, with an inlet valve adapted to co-act with the coupling connection in the chamber so as to open into communication therewith, and at its top, the drum is provided with an exhaust valve so connectible with said inlet valve as to be opened by the movement thereof, both said inlet and exhaust valves being arranged to close automatically directly the drum is raised for withdrawal from the chamber.

In one constructional embodiment of the invention, for example, a nozzle to admit steam or heated air, as the case may be, into the chamber is secured to the bottom thereof and terminates interiorly thereof in a hollow pedestal or head with the underside of which there co-acts a spring-loaded disc-valve making a fluid-tight joint therewith and slidably axially of the nozzle, the upper surface of said disc-valve being provided with a marginal gasket or jointing ring for contact with the base of a dressing drum when superimposed thereon.

The dressing drum which may be of circular, rectangular or other configuration, is apertured centrally at its base sufficiently to permit the passage of the aforesaid pedestal head and is closed

2

by a disc-valve carried at the foot of a stem extending freely upwardly of a guide tube supported centrally of the drum, and the cover of the drum is also apertured centrally and has fitted therein a spring-urged exhaust valve having a depending stem adapted when the drum cover is closed to make a joint with said upwardly extending valve stem and to function concurrently therewith. Both valves are faced with rubber or other suitable material to form a seal and the valve in the base of the drum is of larger diameter than the valve in the head thereof.

At the top and bottom faces of each drum a groove or bead is formed in order to enable drums to be stacked in the chamber in tiers of two or more.

The aforesaid hollow pedestal and its associated admission valve constitutes an automatic coupling between the chamber and a dressings drum, and one or more of such pedestals and valves may be arranged in the base of the sterilizing chamber, and the drums may be stacked thereon in tiers, the steam passing upwardly through successive drums and escaping from the uppermost one of each tier into the surrounding chamber.

In an alternative embodiment of the invention the valve action of the coupling in the base of the sterilizing chamber may be dispensed with and the steam and air supply may be controlled by a valve situated externally of the chamber.

Further, the stems of the inlet and exhaust valves in the drum may be omitted and the valves may be guided by central bosses, serrated edges, or perforated flanges housed in a perforated cage, the valves being opened by the application of the steam or air pressure and the spring on the inlet valve being dispensed with if desired. Preferably the edge of the inlet valve is so constructed or arranged that a drum cannot be lifted by a person grasping the edge of the valve.

The invention is illustrated by way of example in the accompanying drawings, in which, Figure 1 is a vertical section of one form of connection for the admission of the sterilizing or drying fluid into a dressings drum, the chamber as such being omitted, Figure 2 is a vertical section of a dressings drum, and Figure 3 is a similar view of a modified construction of connection which may be employed between the chamber and drum.

Figure 4 is a diagrammatic sectional view showing three tiers of dressings drums disposed in series above a common sterilizing or drying fluid

connection, the chamber as such being omitted from this view also.

Referring firstly to Figure 1, the base of a sterilizing chamber of orthodox or any convenient design, a portion of which is shown at 1, is apertured to receive a tube or nozzle 2 to admit steam or heated air, as the case may be, which tube or nozzle is fixed in position to extend upwardly into the chamber wherein it terminates interiorly of an inverted flanged circular head 3 screwed on to a spider 4 centrally into which the upper end of the nozzle 2 is screwed, and below the head 3 a circular disc 5 of larger diameter than the head is secured to a sleeve 6 slidable axially of and surrounding the tube or nozzle 2 with the outer surface of which a pressure-tight joint is obtained by means of a gland packing 7 and washer 8 compressed into a bored length of the sleeve by a gland nut 9.

A compression spring 10 confined between the bottom wall 1 of the chamber and the underside of the disc 5 serves normally to maintain the upper surface of the disc 5 in fluid-tight contact with a resilient ring 11 set in a groove in the underside of the spider 4, and the disc 5 is provided with a marginal annular wall 12 in a groove on the top side of which a gasket or jointing ring 13 of rubber or other resilient material is set.

The above described structure constitutes a pedestal upon which a dressings drum of this invention is adapted to be placed.

This dressings drum, see Figure 2, consists of an open topped circular casing 14 to which a lid 15 is hinged at 16 and has one or more clip fasteners such as 17, and the bottom of the casing 14 is apertured centrally at 18 sufficiently to permit the entry within its beaded edge of the pedestal head 3. A tubular guide 19 is held axially of the drum by means of a spider 20 secured at 21 to the base of the drum marginally of the aperture 18.

Inwardly of the base of the drum a disc-valve 22 is seated on the beaded edge of the aperture 18 and is provided with a tubular stem 23 fitting slidably within the tubular guide 19 and closed at its upper end by a conical-ended plug 24,

The lid 15 of the drum is also apertured centrally at 25 and has a disc-valve 26 seated on the upper side of its beaded edge and provided with a depending stem 27 terminating in a conical recess 28 located co-axially above the locating plug 24. A spider 29 surrounding the stem 27 is fixed at 30 below the aperture 25 in the lid 15 and provides a guide for the valve stem and one abutment for a coiled spring 31 confined between it and a collar 32 rigid with the stem 27, the spring serving normally to maintain the valve 26 upon its seating.

Both the valves 22 and 26 may be faced with rubber or other suitable resilient material to form a sealed joint when closed, and the valve 22 in the base of the drum is of greater diameter than the valve 26 in the lid.

The bottom of the drum is formed with a circular groove 33 and the lid is formed with a circular rib 34 of the same radius, in order to enable drums to be stacked in tiers of two or more within the chamber. Furthermore the drum is formed near its lower end with a peripheral rib 35.

In the operation of the above described form of the invention a drum 14 is charged with dressings to be sterilized and after the lid 15 has been closed and made fast, the drum is carried into the chamber and placed on the pedestal with the bottom of the drum resting on the sealing ring 13

on the disc-valve 5 and with the head 3 entering the aperture 18 in the bottom of the drum, and directly the whole weight of the drum and its contents are borne by the pedestal the tension in the spring 10 is overcome and the disc-valve 5 is moved axially downwards thus breaking the joint made by the ring 11 while simultaneously the head 3 of the pedestal contacts with the inlet valve 22 in the base of the drum and presses it upwardly and by the axial movement thus imparted to the stem 23 and locating plug 24 axial pressure is imposed on the stem 27 of the exhaust valve 26 in the lid 15 of the drum and the latter valve is raised from its seating against the tension in the spring 31.

On the opening of the aforesaid valves, as described, the steam immediately flows from the nozzle 2 through the separated elements of the pedestal into the base of the drum upwardly of the interior of which it spreads, expelling the air meanwhile through the open exhaust valve 25 in the lid 15 into the surrounding chamber, and when the contents of the drum have been exposed to the steam for the requisite period of time the operation is instantaneously arrested by lifting the drum off the pedestal whereupon all the valves concerned are immediately returned by spring pressure to the normal closed position and the drum is withdrawn from the chamber.

In an alternative and simpler embodiment of the invention, which may be preferable in some circumstances, the valve action in the pedestal connection is dispensed with, as will be seen by reference to Figure 3 of the drawings.

In this case a steam supply pipe 36 having a control valve (not shown) at a point externally of the chamber leads into a depending manifold 37 housing a concentric baffle tube 38 secured below a disc 39 apertured centrally at 40 and supporting a hollow crown 41 perforated at 42 and constituting the counterpart of the previously described pedestal head 3, and secured by angle rings 43 on the upper face of the disc 39 is a resilient jointing ring 44 upon which the base of the drum 15 is adapted to seat in a fluid-tight manner.

The disc 39 is borne by an annular upwardly flanged plate 45 within the upper part of which is disposed a ring 46 serving to locate the lower end of a drum 15 which is adapted to pass thereinto until the peripheral rib 35 on the drum contacts the upper edge of the locating ring, and when this occurs the inlet valve 22 in the base of the drum and the exhaust valve 26 in the lid of the drum are forced open in the manner already described, whereupon the control valve is opened and the steam flows through the connection into and upwardly through the drum precisely as before and with the same effect. As however this connection is non-automatic the steam is turned off at the control valve before the drum is removed from the pedestal for withdrawal from the chamber.

As has already been stated the drums may be stacked in tiers within the chamber and Figure 4 shows diagrammatically the effect obtained by stacking three drums on one of the connections or pedestals illustrated in Figure 3. In this case the positioning of the bottom drum on the pedestal raises the exhaust valve 26 on the lid of the drum sufficiently to enable it to afford an abutment for the inlet valve 22 in the base of the intermediate drum which is thereby caused to open when the latter drum is set in position, and a similar effect is obtained by the positioning of

the topmost drum, whereafter the control valve is opened to admit the steam through the perforated pedestal head 41 whence it flows upwardly through the series of drums in succession, expelling the air from one to the next and ultimately filling the series of drums. After the goods have been subjected to the sterilizing medium for the prescribed period of time the control valve is shut off and the drums are withdrawn one by one from the chamber, the inlet and exhaust valves in each drum closing automatically and sealing each drum against contamination of the goods by the atmosphere immediately the weight of a drum is removed from the drum below.

It will be seen that in both sterilizing and drying the goods the treatment is effected by the direct application of the medium in an upward direction, the expulsion of the air at the disinfecting stage being instantaneous and certain immediately the steam fills the drum, and at the drying stage the goods are dried more speedily and thoroughly by virtue of the direct contact of the heated air with the goods. A further advantage is that no vacuum-producing apparatus is necessary in either case.

What I claim is:

1. Sterilizing, disinfecting and drying apparatus of the kind embodying an enclosed chamber to receive at least one container for articles to be treated and having a base into which a fluid medium admission connection is led; characterized by a seating within said base of said chamber to receive said container and located around said fluid admission connection, a pedestal member projecting above said seating, said pedestal member communicating with said fluid medium admission connection, a valve in said container to admit fluid medium thereinto, and a valve in said container to release fluid medium therefrom, both said valves being operated by said pedestal member when said container is positioned upon said seating.

2. Sterilizing, disinfecting and drying apparatus of the kind embodying an enclosed chamber to receive at least one container for articles to be treated and having a base into which a fluid medium admission connection is led; characterized by a seating within said base of said chamber to receive said container and located around said fluid admission connection, a pedestal member projecting above said seating, said pedestal member communicating with said fluid medium admission connection, a fluid medium admission aperture in the base of said container, a fluid medium outlet aperture in the top of said container, an inlet valve controlling said admission aperture, an outlet valve controlling said outlet aperture, co-operating stems between said valves, and guide means to maintain the alignment of said co-operating stems, both said valves being operated by said pedestal member when the container is positioned upon said seating.

3. Sterilizing, disinfecting and drying apparatus of the kind embodying an enclosed chamber to receive at least one container for articles to be treated and having a base into which a fluid medium admission connection is led; characterized by a seating within said base of said chamber to receive said container and located around said fluid admission connection, a pedestal member projecting above said seating, said pedestal member communicating with said fluid medium admission connection, a fluid medium admission aperture in the base of said container, a fluid medium outlet aperture in the top of said con-

tainer, a normally closed fluid medium inlet valve seated on said admission aperture, a normally closed fluid medium outlet valve seated on said outlet aperture, a valve stem upstanding from said inlet valve, a valve stem depending from said outlet valve, and a tubular guide member co-aligning said stems, both said valves being operated by said pedestal member when the container is positioned on the seating.

4. Sterilizing, disinfecting and drying apparatus of the kind embodying an enclosed chamber to receive at least one container for articles to be treated and having a base into which a fluid medium admission connection is led; characterized by a seating within said base of said chamber to receive said container and located around said fluid admission connection, a pedestal member projecting above said seating in said chamber, said pedestal member communicating with said fluid medium admission connection, a fluid medium admission aperture in the base of said container, said admission aperture being capable of receiving said pedestal member within it, a fluid medium outlet aperture in the top of said container, a normally closed fluid medium inlet valve seated on said inlet aperture, a normally closed fluid medium outlet valve seated on said outlet aperture, said outlet valve opening against spring pressure, a valve stem extending upwardly of said inlet valve, a fixed tubular guide enclosing said inlet valve stem, a valve stem depending from said outlet valve in alignment with said inlet valve stem, a conical locating tip on the upper end of said inlet valve stem, and a conical locating recess on the lower end of said outlet valve stem, both said valves being operated by said pedestal member when the container is positioned on said seating.

5. Sterilizing, disinfecting and drying apparatus of the kind embodying an enclosed chamber, to receive at least one container for articles to be treated and having a base into which a fluid medium admission tube is led; characterized by a pedestal member mounted on said tube, said pedestal member communicating with said fluid medium admission tube, a seating to receive said container mounted resiliently about said admission tube below said pedestal member thereon, a resilient sealing ring around the upper face of said seating, a resilient sealing ring between the lower face of said head and the upper face of said seating, a fluid medium admission aperture in the base of said container, said aperture being capable of receiving said pedestal member within it, a fluid medium outlet aperture in the top of said container, and normally closed fluid medium inlet and outlet valves seated respectively on said inlet and outlet apertures, both said valves being operated by said pedestal member when the container is placed on said seating.

6. Sterilizing, disinfecting and drying apparatus of the kind embodying an enclosed chamber to receive at least one container for articles to be treated within said chamber and having a base into which a fluid medium admission tube is led; characterized by a fluid medium inlet valve in said container, a fluid medium release valve in said container, a fluid medium admission coupling within said base of said chamber, a part of said coupling serving as a seating to receive said container, and a part of said coupling being a pedestal member, said pedestal member contacting said fluid medium inlet valve to lift it from its seat when the container is placed over the pedestal.

7. Sterilizing, disinfecting and drying apparatus of the kind embodying an enclosed chamber to receive a plurality of superimposed containers for articles to be treated and having a base into which a fluid medium admission tube is led; characterized by a fluid medium inlet valve in each of said containers, a fluid medium outlet valve in each of said containers, a fluid medium admission coupling within said base of said chamber, a part of said coupling serving as a seating to receive the lowermost of said containers, and a part of said coupling being a pedestal member, said pedestal member contacting the fluid medium inlet valve of the lowermost of said containers to lift it and the outlet valve from their seats when said lowermost container is placed over the pedestal and the valves of each succeeding container being actuated by the outlet valve of the container on to which it is placed.

8. Sterilizing, disinfecting and drying apparatus of the kind embodying an enclosed chamber to receive at least one sealed container for articles to be treated with a fluid medium admitted through the base of said chamber; characterized by a fluid medium admission aperture in the base of said container, a fluid medium inlet valve seated on said admission aperture, a fluid medium outlet aperture in the top of said container, a fluid medium outlet valve seated on said outlet aperture, said two valves having oppositely disposed co-aligned valve stems, a fluid medium admission coupling within said base of said chamber, a part of said coupling serving as a seating to receive said container, and a part of said coupling being a pedestal projecting above said seating, said pedestal contacting said fluid medium inlet valve to lift it together with said

fluid medium outlet valve from their respective seatings when the container is placed over the pedestal.

9. Sterilizing, disinfecting and drying apparatus of the kind embodying an enclosed chamber to receive at least one sealed container for articles to be treated with a fluid medium admitted through the base of said chamber; characterized by a container consisting of a metal drum having a hinged lid, a fluid medium admission aperture in the base of said container, a fluid medium inlet valve seated on said admission aperture, a fluid medium outlet aperture in the lid of said container, a fluid medium outlet valve seated on said outlet aperture, said two valves having oppositely disposed co-aligned valve stems, a fluid medium admission coupling within said base of said chamber, said coupling comprising a seating for said container and a pedestal member projecting above said seating, and said pedestal member passing into the fluid medium admission aperture in the base of said container and contacting said fluid medium inlet valve to lift it together with said fluid medium outlet valve from their respective seatings when the container is placed over the pedestal member.
